UNITED STATES PATENT OFFICE.

CHARLES E. BONSOR, OF LORAIN, OHIO.

FURNACE-ROOF CONSTRUCTION.

1,330,052.

Specification of Letters Patent. Patented Feb. 10, 1920.

Application filed September 19, 1910. Serial No. 254,790.

To all whom it may concern:

Be it known that I, CHARLES E. BONSOR, a citizen of the United States, and resident of Lorain, in the county of Lorain and State of Ohio, have invented certain new and useful Improvements in Furnace-Roof Constructions, of which the following is a specification.

My invention relates to the construction 10 of the transversely arched roofs of melting, heating, annealing and similar furnaces, and more particularly relates to the construction of the skewback supports and the refractory skewbacks used in carrying and transmitting the thrust of such arched roofs to the side walls and metal framework of such furnaces.

It has been the general practice heretofore, in constructing the roofs of such furnaces, which are made of fire-brick or similar refractory materials, to position the skewbacks against lengthwise horizontal skewback supports to maintain the refractory skewbacks in place and prevent downward movement thereof relative to the skewback supports. After the furnaces have been used for any considerable time the lower edges of the metal skewback supports and adjacent refractory skewbacks burn 25 away, particularly at points immediately above the door-ways in one or both of the furnace side walls. The result is that the skewbacks or a portion of the skewbacks will slip or fall downwardly and become 30 displaced in relation to the skewback supports and will permit the arched roof to fall in part and cause great liability of collapse of portions and sometimes of the entire roof. Such happenings are the cause 35 of long delays in the operation of the furnaces while rebuilding or making repairs, and the source of great expense in maintaining the furnaces in operative condition. One object of this invention is to provide 40 a refractory skewback and skewback support of improved construction and having novel means whereby the skewbacks are maintained in position against the skewback supports and whereby the life of the 45 skewbacks and skewback supports is materially increased, liability of damage of the roof by reason of disarrangement of the skewbacks relative to the skewback supports is avoided and overcome, and the life of the 50 furnace roofs is greatly lengthened.

Another object of my invention is the provision in an arched furnace roof of skewback supports and coating skewbacks having the novel constructions, arrangements and combination of parts shown in the drawings, 60 to be fully described hereinafter, and to be particularly pointed out in the appended claims.

Referring now to the drawings, forming part of this specification, Figure 1 is a sectional end elevation of a furnace having an arched roof formed of refractory material, and constructed in accordance with my invention.

Fig. 2 is a sectional end elevation, on a larger scale, showing details in the construction and arrangement of skewbacks and skewback supports embodying my invention.

Fig. 3 is a perspective view showing further details in the construction of the refractory skewbacks forming part of this invention.

Fig. 4 is a plan showing a preferred form of skewback supports constructed in accordance with my invention.

Fig. 5 is an end elevation of the skewback support shown in Fig. 4.

In the accompanying drawings, the letter A designates generally, a furnace having an arched roof 2, side walls 3 and 4, and a bottom 5, formed of refractory materials. The ends of the roof arch engage with and are supported on the inclined side faces 6 of my improved skewbacks B, the skewbacks B being provided at each side of the furnace and having one vertical face 7 in close contact with the contiguous faces of the skewback supports C. The skewbacks B are notched in the intersection of the vertical side with the lower end thereof to form a rabbet 8, this rabbet being provided to receive the inturned flange 9 on the lower edge of the web 10 of the skewback support C. The outer vertical face 7 of the skewback also is provided with a transverse slot or groove 11 therein to receive the rib or projection 12 on the contiguous face of the web of the skewback support C.

The web 10 of the skewback support C has inturned flanges 9, 9, on its opposite marginal edges, the support C being channel shaped in cross-section. Preferably the support C will be made of cast metal with the web and flanges of material thickness to

provide considerable body in these supports. When preferred, however, a rolled steel channel or a built up channel may be used in forming the supports C, instead of a casting, 5 as shown. The skewback support C at an intermediate point in the width of its web has a rib or projection 12, this rib having one face 13 extending substantially at right angles to the plane of the inner surface of 10 the web of the support. The other face 14 of this projection 12 extends in a flat plane at an oblique angle to that of the side surface 13, and the so-formed rib or projection extends into and substantially 15 fills the similarly shaped transverse groove 11 in the contacting face of the skewbacks B. (See Figs. 2, 3, 4, and 5).

In building the furnaces, the skewback supports C are bolted or otherwise fastened 20 to the vertical buck-stays 15, these buck- stays being used to bind the refractory side walls of the furnace in place. Each buck- stay 15 is fastened at its ends to the ends of 25 an opposite buck-stay on the opposite side of the furnace by a horizontal tie-rod or bolt 16 in the usual and well-known manner, and as the metal framework of the furnace is generally a self-supporting structure, the lower ends of the buck-stays 15 30 will be supported on and fastened to the over-hanging ends of the horizontal beams 17 thereof. The beams 17 are carried on a suitable foundation, as is clearly shown in Fig. 1.

When building the transversely arched roofs, the skewbacks B are placed in position against the skewback supports C with the lower flange 9 and the projecting rib 12 of the skewback support in the rabbet 8, 35 and transverse slot or groove 11 in the side of the skewbacks B. The roof bricks are then put in place across the width of the furnace to form the arched roof 2, the thrust of the arch taken by the skewbacks B and 40 transmitted by the skewbacks to the skewback supports C and furnace walls 3 and 4. As shown the skewback supports and skewbacks and buck-stays are capable of supporting the roof independently of the 45 furnace walls 2, 3, although the side walls 50 are built up until in close contact with the ends of the arched roof, in the usual and well-known manner.

When, as occurs after extended use, the 55 lower flanges 9 on the skewback supports C burn away, the rib 12 on the web of the skewback supports securely holds the skewbacks B in position and prevents downward movement of the skewbacks relative to the 60 skewback supports.

The advantages of my invention will be appreciated by those skilled in the art. By constructing the skewback supports and skewbacks as shown and described, the life 65 of the refractory furnace roofs, of which

my improved skewbacks form part, is very materially lengthened and the cost of operating the furnaces greatly reduced.

Various modifications in the construction of the skewback supports and skewbacks 70 may be made without departing from my invention. The rib on the web of the skewback supports may be bolted or otherwise fastened thereon instead of being formed integrally on the skewback support as shown, 75 and other changes may be made within the scope of the appended claims.

I claim:—

1. In a metallurgical furnace having refractory side walls and an arched roof of refractory material, the combination with the skewbacks at the ends of the roof arch, of skewback supports engaging the sides of the skewbacks, said skewback supports being arranged to resist the thrust of said roof, and said skewbacks and skewback supports having a plurality of registering projections and grooves in the meeting faces thereof arranged to oppose movement of the skewbacks relative to said supports. 90

2. In a metallurgical furnace having refractory side walls and an arched roof of refractory material, the combination with the skewbacks at the ends of the roof arch, of skewback supports engaging the sides 95 of the skewbacks and arranged to resist the thrust of said roof, said skewbacks having a plurality of transverse grooves in the support side thereof and said skewback supports having projections thereon adapted to 100 project into said grooves and prevent movement of the skewbacks relative to the skewback supports.

3. In a metallurgical furnace having refractory side walls and an arched roof of refractory material, the combination with the skewbacks at the ends of the roof arch, of skewback supports engaging the sides of the skewbacks and arranged to resist the thrust of said roof, said skewbacks having 105 a plurality of transverse grooves in the support side thereof and said skewback supports having integral projections thereon adapted to project into said grooves and prevent movement of the skewbacks relative 110 to the skewback supports.

4. In a metallurgical furnace, the combination with the skewbacks at the ends of the roof arch, of skewback supports to which the thrust of the roof arch is transmitted by said skewbacks, said skewback supports comprising a body portion channel shaped in cross section, and having a rib formed integral with the web of said channel shaped body portion intermediate its 125 flanges.

5. In a metallurgical furnace having refractory side walls and an arched roof of refractory material, the combination with the skewbacks at the ends of the roof arch, 130

of skewback supports to which the thrust of the roof arch is transmitted by said skewbacks, said skewbacks having a plurality of transverse grooves in one face and 5 said skewback supports having integral projections thereon adapted to enter said grooves and oppose relative movement of said skewbacks and skewback supports.

6. In an arched furnace roof, the combination 10 with the skewbacks at the ends of the roof arch, of skewback supports to which the thrust of the roof arch is transmitted by said skewbacks, said skewback supports having a main supporting projection and a 15 supplemental projection, both of said projections having an interlocking engagement with said skewbacks.

7. In a metallurgical furnace having side 20 walls and an arched roof, the combination of refractory skewbacks at the ends of the roof arch, of skewback supports to which the thrust of the roof arch is transmitted by said skewbacks, said skewback supports having the bottom edge turned inwardly 25 substantially at right angles to the web thereof to form a main support and having a projection on said web adapted to engage in grooves in said skewbacks and form a supplemental support.

8. In an arched furnace roof, the combination 30 with the skewbacks at the ends of the roof arch, of skewback supports to which the thrust of the roof arch is trans-

mitted by said skewbacks, said skewback supports comprising a web portion, top 35 and bottom flanges extending inwardly at right angles to said web portion, and a rib formed integral with and projecting inwardly from said web intermediate said flanges, said bottom flange and said rib 40 having an interlocking engagement with said skewbacks.

9. A skewback support comprising a web portion, top and bottom flanges extending 45 inwardly at right angles to said web portion, and a rib formed integral with said web portion intermediate said flanges, the bottom face of said rib extending at right angles to the plane of the inner surface of 50 said web, and the other face thereof extending inwardly and downwardly on an angle.

10. In a metallurgical furnace having an arched roof, the combination with the skewbacks at the ends of the roof arch, of skewback supports engaging the sides of the 55 skewbacks, said skewback supports comprising a web portion, top and bottom flanges extending inwardly at right angles to said web portion, and an intermediate rib formed integral with the inner face of said web, 60 the bottom flange and said rib having interlocking engagement with said skewbacks.

In testimony whereof I have hereunto set my hand.

CHARLES E. BONSOR.
